MOTOR COMPRESSOR UNIT

Jens Touborg, Tecumseh, Mich., assignor to Gibson Electric Refrigerator Corporation, Green-ville, Mich., a corporation of Michigan

Application December 16, 1937, Serial No. 180,247

4 Claims. (Cl. 230—206)

This invention relates to improvements in motor compressor units and more especially such a device particularly adapted for compressing or pumping fluids. The device may be used, for example, for compressing a fluid used in refrigerating apparatus, such as ammonia, freon, methyl chloride, or the like.

Among the features of my invention is the provision of a single cylinder compressor driven by a shaft lying in a relatively long sleeve forming a single bearing for the shaft. One end of the shaft carries the crank operating the compressor and the other end carries the armature of the driving motor.

Another feature of my invention is the provision of improved oiling means comprising in general an oil hole or duct beginning at the bottom inside edge of the crank pin and leading diagonally upwardly and through the crank pin to a spiral groove on the shaft. Since the inlet to the hole is substantially at the center of rotation while the outlet is approximately one-half inch away from the center of rotation, oil is drawn into and forced through the hole up into the bearing by means of centrifugal force where it is picked up by the spiral groove and properly distributed throughout the bearing.

Another feature of the invention is the provision of a piston and yoke construction of the Scotch yoke type with means for lubricating the piston and cross-slide by submerging them in oil.

Another feature of the invention is the provision of a single casting serving as a casing for the compressor and as a support for the motor stator. This casing also supports the main sleeve bearing above described.

Another feature of the invention is the provision of a base casting bolted to the frame casting with a gasket so that it also forms a part of the compressor casing; the entire casing for the motor compressor until being hermetically sealed.

Another feature of the invention is improved means for closing the upper end of the frame casting by means of a cap screwed into the casting. The parts are machined so that the rim of the cap seats tightly against the frame casting in such a way as to compress a round rubber ring or gasket tightly into a recess provided therefor. This provides an excellent gas-tight closure and has the further advantage of providing compactness and neatness of appearance. This construction replaces the older type using flanges with a gasket held together by a large number of bolts. The screw seal gives more uniform pressure on the gasket and makes a better seal.

Other features and advantages will appear more fully as I proceed with my specification.

In that form of device embodying the features of my invention shown in the accompanying drawings—Fig. 1 is a view in side elevation; Fig. 2 is a view taken as indicated by the line 2 of Fig. 1; Fig. 3 is a view taken as indicated by the line 3 of Fig. 1; Fig. 4 is a view taken as indicated by the line 4 of Fig. 1; Fig. 5 is a view taken as indicated by the line 5 of Fig. 3; Fig. 6 is a view taken as indicated by the line 6 of Fig. 3; Fig. 7 is a view taken as indicated by the line 7 of Fig. 3; Fig. 8 is a vertical sectional view taken through the crank pin; and Figs. 9 and 10 show the inlet valve for the compressor.

As shown in the drawings, the unit comprises principally a cylindrical frame casting A open at the top and bottom, with a threaded cap B to close the top and a base casting C in the form of a plate bolted to the lower end to close the bottom. D indicates a cylinder radially inserted in the casting A near the lower end and held in position by the cap screws 10, 10, 11, 11 indicate the cap screws holding the base plate C in position, and 12 indicates a gasket between the base plate and the lower end of the casting A to make a tight connection. E indicates a head for the cylinder D which is also held in position by the cap screws 10.

The periphery of the cap B is provided with external threads screwing into internal threads at the upper end of the frame or main casting A. The lower edge of the cap B is slightly beveled at its periphery on the outside as indicated by 13. 14 indicates a shoulder on the inner side of the upper end of the casting A below the threads, the lower edge of the bevel 13 adapted to seat against said shoulder. 15 indicates a round rubber ring or gasket which is tightly compressed in the space between the bevel 13, the shoulder 14 and the inner wall of the casting A when the cap B is screwed into place. As shown in Fig. 3, this gasket is compressed so that its cross section is distorted from a substantially circular one to a substantially triangular one. This makes an hermetic seal between the cap B and the upper end of the cylindrical casing A.

The cylinder D and its head E are secured tightly in position by means of the cap screws 10, suitable gaskets or ground joints being provided to hermetically seal the parts. Likewise the gasket 12 serves to hermetically seal the base plate C over the lower end of the casing A. It will thus be seen that there is provided by the parts so far described an hermetically sealed casing which

completely houses the motor and compressor to be hereinafter described.

The casing A is provided at about the center or a short distance below the center with a 5 spider or perforated diaphragm 16 supporting the lower end of a centrally arranged tubular or sleeve bearing 17. 16a, 16a indicate radial strengthening ribs on the underside of the perforated diaphragm 16.

10 When the confined gasket 15 has been compressed into the machined recess in the casting it becomes vulcanized by heat due to the dehydrating baking process and also by heat generated by the operation of the compressor. This serves 15 to make a very good seal.

The removable cylinder D has been described above. This cylinder is formed by a hole bored in a casting which is separate and removable from the main frame casting A. It is held in place by 20 the cap screws 10. A distinct advantage of this construction is that it is possible to easily and quickly exchange a worn or damaged cylinder for a new one, also to exchange one cylinder for another of different size in order to change the 25 displacement and resulting pumping capacity of the compressor whenever desirable.

18 indicates a vertical shaft in the sleeve bearing 17 carrying on its lower end the crank pin or eccentric 19 operating through the hollow cylindrical yoke 20 and cylindrical crosshead 21 to reciprocate the piston 22 in the cylinder D. In a broad sense the crank pin or eccentric 19 is considered as an extension or part of the shaft 18. 23 indicates a member centered on the 30 crank pin 19 with respect to the axis of the shaft 18 to form a thrust bearing for the shaft and associated parts. The lower end of this member rests against the center of the base plate C.

The upper end of the shaft 18 carries the 35 electrical motor rotor 24 and this preferably depends somewhat so that it overlaps the upper end of the sleeve bearing 17. Outside of the rotor 24 is the stator 25 carried on the inside of the casing A. 26 indicates one of the electrical connections to the stator 25, the other not being shown. The 40 electrical connections are carried through the wall of the casing A and suitably insulated and hermetically sealed.

27 indicates an oil duct with its lower end at 45 the bottom inside edge of the crank pin 19 leading diagonally upwardly through the crank pin to the lower end of the spiral groove 28 on the shaft. The lower end of the duct 27 lies substantially in alignment with the axis of the shaft 18. The 50 upper end of this groove is about one-half inch away from the center of rotation. Because of this construction, oil is drawn into and forced through the hole 27 up into the bearing by means of centrifugal force where it is picked up by the spiral groove 28 and properly distributed throughout the length of the sleeve bearing 17.

The piston, cross slide and crank pin receive 55 their lubrication by virtue of the fact that they run practically submerged in oil. That is, a pool of oil stands in the lower part of the casing as indicated by 58. The level of this oil is maintained preferably about up to the inlet opening 29.

29 indicates the inlet to the casing through 60 which the fluid to be compressed is drawn. From the interior of the casing the fluid enters the compression cylinder D through the port 30 as shown in Fig. 2. The compressed fluid leaves the cylinder E after compression through the port 31 which leads to the port 32 connecting with the

outlet 33 as shown in Fig. 4. 34 indicates a suitable outlet valve for the compressor cylinder. 35 indicates a by-pass controlled by the unloader valves 36 which are not described here as they constitute no part of the present invention. The 5 inlet valve for the compressor is in the form of a wafer flapper as shown in the drawings; but since the details of this valve form no part of the present invention they need not be described here. It is to be understood that the compressor cylinder D may be provided with any suitable inlet and outlet valves. 10

The base plate C is provided with four integrally-formed arms 51, 51 provided with holes 52 in their ends adapted to receive mounting 15 bolts or screws for suitably supporting the unit in position on any suitable foundation or base. The base plate C with the arms 51 are preferably formed of one casting which is screwed to the bottom of the main casing A by the screws 11 20 to hermetically seal the bottom of the casing and also form a suitable base for the unit. 25

The piston 22 with its skirt 22a and the hollow cylindrical yoke 20 are all cast in one piece, the latter being provided with slots 20a to accommodate the crank pin 19 during the reciprocations of the crosshead 21 in the yoke 20. The yoke 20 is also provided with an aperture 20b at one side to permit entry of oil 58 to the crosshead; and the yoke near its top at the other side is also 30 provided with an oil duct 20c.

The casing A, sleeve bearing 17 and diaphragm 16 supporting the same are all formed of one integral casting. 16b, 16b indicate holes in the diaphragm 16. 35

55 may indicate a gasket between the flange 55 of the cylinder D and the casing A in order to make a tight joint; and there may also be a gasket 57 between the cylinder D and the cylinder head E. 40

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art. 45

50 What I claim as new, and desire to secure by Letters Patent, is:

1. A motor compressor unit, including: a vertical cylindrical casing; a radial compressor cylinder in the casing near its lower end; a vertical sleeve bearing axially located in the casing; a shaft in the sleeve bearing; a piston in the cylinder; a driving connection between the lower end of the shaft and the piston, including a crank pin on the shaft with an oil duct therein with its lower end open and adapted to be submerged in a pool of oil in the lower part of the casing and its upper end leading to the sleeve bearing, the lower end of said duct being nearer the axis of rotation of the shaft than the upper end; a rotor carried by the upper end of the shaft; and a stator in the casing and surrounding the rotor. 55

2. A motor compressor unit, including: a vertical cylindrical casing adapted to contain a pool of oil in the lower part thereof; a vertical sleeve bearing axially located in the casing; a shaft in the sleeve bearing; a compressor at the bottom of the casing; a driving connection between the shaft and the compressor; means for driving the shaft; and an oil duct leading from 60 65 70 75 80 85 90 95 98

the lower end of the shaft to the sleeve bearing, the lower end of said oil duct being nearer the axis of rotation of the shaft than the upper end, said lower end of said oil duct being open and adapted to be submerged in a pool of oil in the lower part of the casing.

3. A motor compressor unit, including: a vertical cylindrical casing adapted to contain a pool of oil in the lower part thereof; a vertical sleeve bearing axially located in the casing; a shaft in the sleeve bearing; a compressor at the bottom of the casing; a driving connection between the shaft and the compressor; means for driving the shaft; and an oil duct leading from the lower end of the shaft to the sleeve bearing, the lower end of said oil duct being open and the lower portion thereof adapted to be submerged in a pool of oil in the lower part of said casing, a lower part of said submerged portion being nearer the axis of rotation of said shaft than a higher part of said submerged portion, whereby centrifugal action caused by rotation of the shaft will force upwardly oil standing in said lower portion of said duct.

4. A motor compressor unit, including: a vertical cylindrical casing adapted to contain a pool of oil in the lower part thereof; a vertical sleeve bearing axially located in the casing; a shaft in the sleeve bearing; a compressor at the bottom 5 of the casing; a driving connection between the shaft and the compressor; means for driving the shaft; and an oil duct leading from the lower end of the shaft to the sleeve bearing, the lower end of said oil duct being open and the lower portion 10 thereof adapted to be submerged in a pool of oil in the lower part of said casing, a lower part of said submerged portion being nearer the axis of rotation of said shaft than a higher part of said submerged portion, whereby centrifugal action 15 caused by rotation of the shaft will force upwardly oil standing in said lower portion of said duct.
